UNITED STATES PATENT OFFICE.

EDWIN W. GROVE, OF ST. LOUIS, MISSOURI.

DESIGN FOR A TOILET-COMB.

49,117.

Specification for Design.

Patented May 30, 1916.

Application filed February 15, 1916. Serial No. 78,543. Term of patent 14 years.

To all whom it may concern:

Be it known that I, EDWIN W. GROVE, a citizen of the United States, residing at St. Louis, in the State of Missouri, have invented a new, original, and ornamental Design for Toilet-Combs, of which the following is a specification, reference being had to the accompanying drawing, in which—

Figure 1 is a side elevation of a toilet comb embodying my new design; Fig. 2 is a top plan view thereof; and Fig. 3 is an end elevation thereof.

I claim:—

The ornamental design for a toilet comb, as shown.

EDWIN W. GROVE.
